By George Thorpe Esq. M.P.

UNITED STATES PATENT OFFICE.

EDMUND HALE O'BRIEN, OF KANSAS CITY, MISSOURI.

DOOR-LOCK.

1,340,398.

Specification of Letters Patent. Patented May 18, 1920.

Application filed December 9, 1912. Serial No. 735,677.

To all whom it may concern:

Be it known that I, EDMUND HALE O'BRIEN, a citizen of the United States, residing at Kansas City, in the county of 5 Jackson and State of Missouri, have invented certain new and useful Improvements in Door-Locks, of which the following is a specification.

This invention relates to locks for motor 10 car doors and the like. Heretofore in all locks, as far as I am aware, the latch bolts have been retracted or thrown to inoperative position by striking against the socket plates secured to the door jambs and through 15 such contact the paint or enamel finish of the socket plates, or of the jambs or other parts adjacent thereto, is soon scratched or dislodged.

The object of this invention is to produce 20 a lock in which the bolt after being thrown to inoperative position to permit the door being opened, remains in such position until the door is fully closed and is then thrown to operative position and therefore 25 cannot be instrumental in scratching or otherwise defacing any part of the socket plate or jamb.

A further object is to produce a doorlock 30 in which the shock or jar incident to the arrest of the door as it is closed is cushioned and partially or wholly removed from the socket plate which receives the bolt, or the jamb which carries said plate.

With these objects in view the invention 35 consists in certain novel and peculiar features of construction and organization as hereinafter described and claimed; and in order that it may be fully understood reference is to be had to the accompanying 40 drawings, in which—

Figure 1, is a fragmentary side elevation of a motor car in which the door is broken away to disclose a lock embodying my invention.

Fig. 2, is a horizontal section of the car, to show the lock in plan view.

Fig. 3, is a view of the lock with the face plate removed, and with the bolt advanced, as when the door is closed.

Fig. 4, is a similar view with the bolt retracted and the door still closed.

Fig. 5, is a vertical section taken on the line V—V of Fig. 4.

Fig. 6, is a detail view of a lever forming 55 part of the lock.

Fig. 7, is a detail perspective view of the trigger of the lock.

Fig. 8, is a detail perspective view of a part of a bar for imparting endwise movement to the trigger. 60

Fig. 9, is a detail perspective view of a spring for holding the trigger yieldingly elevated.

Fig. 10, is a detail perspective view of a slide plate forming a part of the lock. 65

In the said drawings, 1 is a lock casing and 2 the removable face plate thereof. 3 is the bolt, the head of the same fitting in an opening in the front wall of the casing, and provided in its upper edge with a 70 notch 5.

The shank of the bolt is provided with a longitudinal slot 6, engaging a guide pin 7, rigid with the casing and projecting laterally and downwardly respectively, from 75 the shank are pins 8 and 9, the latter being connected by a retractile spring 10 with a pin 11 rigid with the casing, the function of the spring being to advance the bolt at the proper time. 80

To lock the bolt in its retracted position, as shown in Fig. 4, a dog or tumbler 12 is mounted pivotally within the casing, and is provided with a depending tooth 13 for engagement with the notch 5, the dog or 85 tumbler being held pressed yieldingly toward the bolt by a spring 14, which is coiled around the pivot pin 15 of the dog, and bears at its ends upon the latter and against the front end wall of the casing. 90 For the purpose of retracting the bolt, a lever 16 is suspended within the casing from pivot 17, and at its lower end bears against the forward side of pin 8 of the bolt, and is connected by a retractile spring 18 to the 95 rear end of the wall of the casing; said spring being of sufficient strength to overcome the resistance of spring 10 and withdraw the bolt 3, when the latter is not held advanced or projected by a preponderating 100 power.

The lever is cut away at 19, to provide a shoulder 20, and projecting through the cut away portion or opening is a trigger or tumbler 21, having a forwardly-disposed 105 shoulder 22 for engagement with shoulder 20 at times. The trigger or tumbler is provided with a longitudinal slot 23 pivotally and slidingly receiving a pin 24 projecting from the casing and it is also provided in its 110

rear end with a vertical slot 25, receiving a pin 26, projecting laterally from the head of a slide bar 27, extending into the casing through the rear end wall thereof, and to assist in holding this slide bar in a substantially horizontal position, it is provided with a longitudinal slot 28, engaging the pin 24 forming the pivot of the trigger 21. Secured to the lower edge of the head of the slide bar is a spring 29, the spring end 30 of the same underlying the trigger 21 and constantly tending to elevate the front end thereof.

Pivoted within the casing on pivot 31 is a bell crank lever 32 and interposed between said lever and the face plate of the casing is a slide plate 33, having a stem 34, projecting slidingly through the top of the casing. This plate is also provided with a vertical slot 35 receiving pivot 31 and a shoulder 36 which rests upon the upper arm of the said bell crank lever, so that when the slide plate is pressed downward, it shall cause the bell crank lever to exert downward pressure on the trigger 21.

When the bolt occupies its advanced or operative position and is engaged with the socket piece 46, as shown in Fig. 3, the trigger is raised and prevents backward swinging movement of lever 16 and the consequent withdrawal of the bolt, and while the trigger is thus advanced its front or free end is held elevated through pressure of its shoulder 22 on shoulder 20 of the lever 16, and the upward pressure of spring 29.

The slide bar 27 is secured in a socket 37 fastened on the front end of a rod 38, which extends for the full width of the car door 39, and when the latter is closed or nearly closed, engages a wear plate 40 secured to the hinge jamb 41, through the pressure of a spring 42 interposed between the socket 37 and the casing 1, and in this connection it will be noted that for all practical purposes rods 27 and 38 are one, but that for convenience in assembling, they are preferably made in sections, as shown in Fig. 3.

For imparting downward movement to the slide plate 33, a push rod 43 extending up through the door, is provided at its lower end with a socket 44 receiving the upper end of the stem of the slide plate, and at its upper end is provided with a head or button 45 projecting slightly beyond the upper edge of the door for convenient operation by a person seated in the car.

Assuming that the bolt is advanced and that pressure is applied on the push rod, the following actions occur;—The plate 33 slides downward and its shoulder 36 rocks the bell crank and causes the latter to swing the trigger downward until tripped from engagement with lever 16. Spring 18 will then swing lever 16 rearwardly and as said spring is of greater power than spring 10,

it withdraws the bolt by rearward pressure on pin 8, and in withdrawing the bolt, stretches or tensions spring 10.

As the lever 16 swings rearwardly and effects the withdrawal of the bolt, dog 12 swings downward until its tooth is in the path of rearward movement of the bolt head so that in the rearward movement of the latter, the dog is pushed upward, and when its tooth registers with notch 5, and it drops down and locks the bolt in its withdrawn or retracted position, as shown in Fig. 4, it being noted that this withdrawal of the bolt occurs without any change of position on the part of the bar 27, which it will be noted is held advanced against the resistance of spring 42 because the rear end of bar 38 bears against the wear plate 40.

As the door is opened the spring 42 imparts rearward movement to bars 27 and 38, and hence to the trigger 21, and as the latter is withdrawn a sufficient distance for its shoulder 22 to clear shoulder 20 of the lever, the spring 29 raises the front end of the trigger and holds it elevated.

Upon the reclosing of the door, the rear end of rod 38 engages and is pushed forward by the wear plate 40, this adjustment of said rod beginning just before and ending as the door is fully closed, and in such movement spring 42 is compressed and the trigger is advanced so that through its pressure on lever 16, the same shall be swung forward and trip the dog from engagement with the bolt.

The tripping of the dog from engagement with the bolt permits the spring 10 to force the bolt into interlocked engagement with the socket plate 46, it being understood that the parts are so proportioned that the tooth of the dog is not wholly withdrawn from the notch 5, until the door is fully closed and the bolt is in perfect alinement with the socket plate.

From the above description it will be apparent that I have produced a door lock embodying the features of advantage enumerated as desirable and I wish it to be understood that I reserve the right to make all changes falling within the principle and scope of the invention as defined by the appended claims.

I claim;

1. In a lock, the combination of a casing, a bolt therein, means holding the bolt in inoperative position, means to trip the bolt-holding means, means to throw the bolt to operative position as the holding means is tripped, and a single means to return the tripping means to original position and the bolt to inoperative position.

2. In a door lock, the combination of a casing, a bolt therein, a pivoted dog holding the bolt in inoperative position, means to

trip said dog, means to throw the bolt to operative position when the dog is tripped, a retractile spring to return the dog-tripping means to original position, and the bolt 5 to inoperative position.

3. In a lock, the combination of a casing, a bolt therein, a lever to move the bolt to inoperative position, means for holding the bolt in inoperative position, means to swing 10 said lever out of the path of advance movement of the bolt and against the said bolt-holding means to trip the same, and a spring to advance or throw the bolt to operative position when said holding means is tripped.

15 4. In a lock, the combination of a casing, a bolt therein, means holding the bolt in inoperative position, a lever in the casing to trip the bolt-holding means, in its advance movement and throw the bolt to inoperative 20 position in its reverse movement, a trigger in the casing to effect the advance movement of the lever and the consequent tripping of the bolt holding means, and a spring to advance the bolt when it is released.

25 5. In a lock, the combination of a casing, a bolt therein, means holding the bolt in inoperative position, a lever in the casing to trip the bolt holding means, in its advance 30 movement, and throw the bolt to inoperative position in its reverse movement, a trigger in the casing to effect the advance movement of the lever and the consequent tripping of the bolt holding means, a spring to 35 advance the bolt when it is released, manually-operable means for tripping the trigger from engagement with the lever, and a spring to swing the lever back to its original position and thereby effect the return of the 40 bolt to its inoperative position.

45 6. In a lock, the combination of a casing, a bolt therein, means holding the bolt in inoperative position, a lever in the casing to trip the bolt holding means in its advance movement, and throw the bolt to inoperative 50 position in its reverse movement, a trigger in the casing to effect the advance movement of the lever and the consequent tripping of the bolt holding means, a spring to advance the bolt when it is released, manually-operable means for tripping the trigger from engagement with the lever, a spring to 55 swing the lever back to its original position and thereby effect the return of the bolt to its inoperative position, and means to restore the trigger to its initial position.

60 7. In a lock, the combination of a casing, a bolt therein, means for holding the bolt in inoperative position, a lever in the casing to trip the bolt holding means in its advance

movement, and throw the bolt to inoperative position in its reverse movement, a trigger in the casing to effect the advance movement of the lever and the consequent tripping of the bolt holding means, a spring to advance 65 the bolt when it is released, manually-operable means for tripping the trigger from engagement with the lever, a spring to swing the lever back to its original position and thereby effect the return of the bolt to its inoperative position, means to withdraw the trigger from its advanced position, and yielding means to restore its free end to the 70 position it occupied prior to being tripped 75 from engagement with said lever.

8. A lock comprising a bolt, resilient means for shooting and drawing the bolt, and means normally projected against the jamb at the hinged edge of the door for controlling 80 said resilient means in projecting the bolt.

9. The combination with a door frame and a door hinged thereto, of means normally holding the door open, means for locking the door to the frame, means for interconnecting and disconnecting said two means, and means for automatically unlocking the door from the frame when said two 85 means are disconnected. 90

10. A door latch, comprising a door locking section, a door opening section, releasable means for interconnecting said sections automatically, and means for retracting the door locking section when said sections are 95 disconnected from each other.

11. The combination with a door frame and a door hinged thereto, of a laterally sliding sectional bolt member mounted on the door and extending across the same, said member being adapted to project beyond either edge of the door, and a spring normally urging said member in the direction of the hinged edge of the door and holding 100 it in contact with the frame. 105

12. In a door latch, the combination of a normally retracted bolt, and door-opening means adapted to cause protraction of the bolt as the door is closed. 110

13. In a door latch, the combination of a normally retracted bolt, and a spring-pressed door-opening bar for causing protraction of the bolt automatically on the closing of the door. 115

In testimony whereof I affix my signature in the presence of two witnesses.

EDMUND HALE O'BRIEN.
